[21] Appl. No.: **81,214**

[57] CLAIM

The ornamental design for a vacuum cleaner, as shown
and described.

[22] Filed: **Oct. 2, 1979**

DESCRIPTION

[30] Foreign Application Priority Data

Apr. 3, 1979 [DE] Fed. Rep. of Germany .... URA 373

[51] Int. Cl. ..... D15—05
[52] U.S. Cl. D32/23
[58] Field of Search ..... D15/52—55,
D15/62—64; 15/320, 321, 324, 325, 327, 347

FIG. 1 is a top side perspective view of a vacuum
cleaner, showing my new design;

FIG. 2 is a top rear perspective view thereof;

FIG. 3 is a bottom perspective view thereof; and

FIG. 4 is a top side perspective view thereof showing

the side opposite that shown in FIG. 2.

The conventional electric cord has been shown frag-
mentarily in FIGS. 1 and 2 for ease of illustration.
